UNITED STATES PATENT OFFICE.

HILLERY K. FLETCHER, OF MONTPELIER, LOUISIANA.

CROSS-TIE FOR RAILWAY-RAILS.

1,083,077.

Specification of Letters Patent.

Patented Dec. 30, 1913.

Application filed January 22, 1913. Serial No. 743,672.

To all whom it may concern:

Be it known that I, HILLERY K. FLETCHER, a citizen of the United States, residing at Montpelier, in the parish of St. Helena and State of Louisiana, have invented new and useful Improvements in Cross-Ties for Railway-Rails, of which the following is a specification.

The present invention relates to improvements in cross ties for railway rails.

In carrying out my invention it is my purpose to construct a tie which shall embody a metallic member that includes parallel sides and an integrally formed bottom as well as cushion members which are arranged between the sides and bottom and upon which the rails rest, and whereby the said rails will be afforded the desired resiliency, the said ties being also provided with integral means whereby the rail securing plates may be securely connected with the tie.

A further object of the invention is the provision of ties for railway rails provided with cushion blocks upon which the rails rest, and also provided with block supporting members that provide spacing elements for at least two of the ties, the said ties being so constructed as to afford an effective connection between the ties and the spacing elements.

With the above recited objects in view, and others which will appear as the nature of the invention is more fully understood the improvement resides in the novel construction, combination and arrangement of parts set forth in the following specification and falling within the scope of the appended claims.

The essential features of the invention involved in carrying out my objects, are necessarily susceptible to changes in size, proportion, and other minor details, but in the accompanying drawings, I have illustrated a satisfactory reduction of my improvement to practice.

In the drawings: Figure 1 is a perspective view of two ties constructed in accordance with my invention, showing the same supporting a single rail, as well as supporting a pair of jointed rails, Fig. 2 is a transverse sectional view taken approximately on the line 2-2 of Fig. 1, Fig. 3 is a longitudinal sectional view on the line 3-3 of Fig. 2, the rails being removed, Fig. 4 is a top plan view of the device as illustrated in Fig. 1, Fig. 5 is a sectional view on the line 5-5 of

Fig. 4, Fig. 6 is a detail perspective view of the metallic portion of the tie, Fig. 7 is a similar view of the combined cushion sustaining and tie spacing member, Fig. 8 is a perspective view illustrating the manner of securing the tie to a bridge chamber or sleeper, and Fig. 9 is a perspective view of a fish plate which may be employed, and looking toward the bottom of said plate.

Referring now to the drawings in detail, the numerals 1 designate the improved ties. The ties comprise each an outer body or casing, which is preferably formed from a substantially rectangular sheet of suitable metal, such as rolled steel or the like. The casing comprises parallel spaced sides 2 and a connecting bottom 3 which is arranged at a right angle to the sides, and the said sides are vertically straight. The sides 2, at a suitable distance from their ends, have their upper edges provided with a pair of spaced slits, the metal between the said slits being downwardly and outwardly bent to provide ledges 4. Each of these ledges is formed with an opening that is arranged adjacent its outer corner, the purpose of the openings will presently be set forth.

Arranged between the sides 2 and resting upon the bottom 3 are cushion members 5. These cushions 5 are each preferably formed from a block of wood, and are shaped to snugly engage within the casing of the tie. The cushions are of a greater thickness than the distance between the upper walls of the ledges 4 and the base or bottom 3 of the tie, so that when the rails R. rest upon the cushions they will not contact with the metallic edges of the sides of the tie. The sides 2 are provided with a plurality of spaced openings, the said openings being adapted for the reception of threaded elements, in the nature of headed wooden screws 6 which enter the opposite sides of the cushions 5. If desired, similar securing means may pass through the bottom 3 to within the lower portions of the cushions 5.

The slotted portions of the sides 2, from which the ledges 4 are formed are spaced from each other a greater distance than is the width of the base flanges of the rails R, and in order to securely connect the rails to the tie, I provide metallic angle bars 7 which have the inner longitudinal walls of their base or lower portions shaped to engage with the longitudinal edges of the base flanges of the rails, and their inner faces

coinciding with the cross sectional shape of the fishing spaces of the rails. These angle bars are provided with openings which are adapted to register with the openings in the ledges 4, the said openings being adapted for the reception of securing elements in the nature of bolts 8 and securing nuts 9.

In order to prevent the accidental separation of the nuts and bolts, incident to the vibration to which the ties will be subjected when the rolling stock passes over the rails which are supported by the ties, I have found it desirable to provide the angle bars with nut locking plates 10. These plates may comprise each a flat substantially rectangular member which has its ends slotted to engage with the heads of the bolts or with the nuts, and the said plates are removably connected with the angle bars through the medium of screw members or through the medium of any other suitable or desired means.

From the above description, when taken in connection with the drawings, it will be noted that the rails R are effectively sustained upon the ties, and as the blocks 5 are each of a width only slightly greater than the length of the ledges 4, the remainder of the tie provides a box-like structure for the reception of the ballast of the roadbed which will effectively prevent either the lateral or longitudinal movement of the ties, and furthermore, that the rails, through the medium of the cushion blocks 5, are afforded the desirable amount of resiliency. It will be further noted that the securing means 6 for the cushion members 5 are removable, and that a worn cushion may be readily removed from the tie and a new cushion substituted therefor.

In order to provide means whereby two rails may be joined between two ties, and also to provide means whereby the said pair of ties are more effectively sustained in spaced relation with each other, I have found it desirable to provide the side members 2 of the metallic portions of the ties with substantially rectangular openings 11 which are disposed below the ledges 4, and which are arranged in a plane with the upper faces of the bottoms 3 of the ties. The numeral 12 designates the connecting member. This member embodies parallel sides 13 and a connecting base 14. The sides 12 terminate each an equal distance from the base 14, the sides being of a length equal to the proper spacing distance between the ties 1, while the base 14 is extended a distance beyond the sides approximately equaling the width of said ties 1. These projecting portions of the base, which may be designated by the numerals 15, are adapted to pass through the openings 11, and the said openings are of a size and shape to snugly receive the said extensions. The extensions 15 are provided

with a plurality of openings corresponding in number with similar openings in the base 3 of the tie 1, while arranged within the member 12 and snugly engaging with the side walls 13 as well as with the base 14 thereof, but projecting a suitable distance above the side walls 12, is a cushion member 16 which is preferably in the nature of a rectangular wooden block. This block is of a length equal to the length of the member 12 between the adjacent inner walls or sides of the ties 1, and is of a thickness corresponding with the thickness of the cushion members 5 within the ties 1. The cushion members 5 may be either of a less thickness than the cushion members previously referred to, or the said cushion members may have their underfaces depressed for the reception of the extending portions 15 of the base 14 of the member 12. The co-acting rails which are arranged upon the cushion 16, and the alining cushions 5, are connected through the medium of angular fish plates 17, the same having their vertical longitudinal walls provided with openings for the reception of the usual securing nuts and bolts, and the lower angular members are provided with openings which register with the openings in the ledges 4 of the ties 1, and furthermore, if desired, the portions of the fish plates between the ties 1 and arranged directly over the member 12 and the cushion 16 thereof may be provided with additional securing means in the nature of the ordinary spikes which enter the cushion 16. Furthermore, if desired, the member 12 may have its sides provided with openings for the reception of securing elements, in the nature of screws or bolts 18, which enter the sides of said cushions 16.

In Fig. 8 I have illustrated a slightly modified form of the device. The tie, in this instance, has its sides formed with outset flanges which are disposed to both the top and bottom edges of the said tie. The lower flanges E are in the same plane with the bottom connecting member C of the tie, and the said flanges F are provided, adjacent the ends of the ties, with spaced openings for the reception of the arms of U-bolts or bails B, the said arms having their ends threaded for the reception of nuts N. The upper flanges F are cut away adjacent the ends of the tie, as are also the sides of the tie, so that the rails R rest upon the cushion block B', without contacting with the metallic tie. The fish plate P, as illustrated in Fig. 9 of the drawing preferably has its underface formed with teeth T which are adapted to be embedded within the cushion member. The plate P is formed with openings adjacent its opposite ends, the said openings being adapted for the reception of securing bolts which are provided with the usual retaining nuts.

Having thus described the invention, what I claim is:

1. A rail tie including a metallic member having parallel sides and an angular base, the sides, adjacent their ends, being depressed and provided with ledges which extend beyond the outer faces of the sides, cushion blocks arranged between the sides and resting upon the bottom and having 10 their upper faces disposed above the ledges, said cushion blocks adapted to provide bearings for the rails, the said rails being further provided with angle bars, and securing elements passing through the ledges and the 15 angle bars.

2. A rail tie including an angular member comprising parallel sides and a right angularly arranged connecting base, the sides, adjacent their ends, being each slotted from 20 their upper edges, the metal between the slits being bent outwardly to provide ledges, cushion blocks arranged between the sides and resting upon the base and projecting above the ledges, said cushion blocks adapted 25 to receive the ties, rail-retaining elements connected with the rails and resting upon the cushions, and securing means between the said elements and the ledges of the sides.

3. In a rail tie, a metallic channel member having its sides, adjacent its ends, provided with ledges, cushion blocks within the channel member and projecting above the ledges, said cushion blocks adapted to provide bearing faces for the rails, the rails 35 being provided with angle bars, and removable securing elements passing through the angle bars and through the ledges and connected with the ledges.

4. In a tie for railway rails, a metallic 40 channel member provided with depressions adjacent its ends and formed with ledges arranged in a plane with the upper walls of the depressions, cushion blocks within the channel members and arranged adjacent the depressions and projecting above the 45 ledges, angle bars for the rails and overlying the cushion blocks, removable securing ele-

ments arranged between the ledges and the angle bars, and a channel member having a rail cushion arranged between two of the ties 50 and connected with the ties.

5. In a tie for railway rails, metallic channel members having their parallel sides, adjacent their ends, depressed and formed with outturned ledges, cushion blocks arranged 55 within the channel members and disposed between the depressed sides thereof and extended beyond the ledges, the sides of each of the channel members below the ledges having openings arranged in a plane 60 with the connecting bottom of said members, channel spacing members, said spacing members having their bases projecting beyond their sides, said projecting members passing through the openings in the channel tie 65 members below the cushion member thereof and secured to the said tie and cushion, a cushion member arranged within the channel connecting member and having its upper wall in a plane with the cushion member 70 of the ties, and the rail ends adapted to rest upon the said cushion member and the cushion members of the tie, angle splice bars for the rail ends, and securing elements passing through the splice bars and the 75 ledges of the ties.

6. A rail tie comprising a metallic channel member having its edges formed with out-turned flanges, a rail supporting cushion within the channel member, means for retaining the cushion within the channel member, fish plates for the rails secured to the tie and to the cushion member, and the lower flanges of the channel member being provided with spaced openings for the reception 80 of securing members for sustaining the tie against movement.

In testimony whereof I affix my signature in presence of two witnesses.

HILLERY K. FLETCHER.
